DECORATIVE HANGING

George F. Brooks, Lakewood, Ohio, assignor to
Industrial Rayon Corporation, Cleveland, Ohio,
a corporation of Delaware

Application September 5, 1935, Serial No. 39,315

2 Claims. (Cl. 156—10)

This invention relates to improvements in decorative hangings such as curtains, draperies, or the like; more particularly, to such hangings made of seamless tubular fabric. Fabric of this type is readily produced, among others, on circular knitting machines. An object of this invention is to provide an article of manufacture comprising a new and improved decorative hanging, as, for example, a window curtain, that can be made easily at very low cost. Other objects will be obvious from the description and drawing, in which are set forth several of the many possible embodiments of the invention.

In the drawing, Figure 1 is an elevation, partly broken away, of a window curtain embodying the invention, the same being formed of seamless tubular fabric. Figure 2 is an elevation, also partly broken away, of a drapery embodying the invention, for convenience in illustration shown flat rather than in the folds or pleats that would ordinarily be expected to be introduced in and as a part of the hanging operation. Figure 3 is a sectional elevation along the line 3—3 of Figure 2. Figure 4 is an elevation of a modified form of decorative hanging likewise embodying the invention.

In the embodiment shown in Figure 1, the invention is illustrated as taking the form of a window curtain comprising a suitable length of seamless tubular fabric 1 which has its ends 2 and 3 closed by any suitable means as, for example, holding threads introduced by a manual or mechanical stitching process. The upper end 2 of the curtain is provided with means for supporting the curtain, as illustratively shown comprising the fold 4 through which is passed the rod 5. In the embodiment shown in Figure 1, the fabric is manufactured in such a way, as on so-called fancy knitting machines, that it has plain bands 6 at the ends 2 and 3 and a design pattern 7 formed in the material between the bands. It is obvious, of course, that any desired design may be used and that if desired the curtain may be made entirely of plain fabric.

Figures 2 and 3 depict another embodiment of the invention, in this case a drapery 10 of seamless tubular fabric. The upper portion 8 of the fabric is shown as doubled over so as to provide an overdrap effect. Rings 9 are provided to support the drapery 10, although it is evident that any other suitable supporting means, such, for instance, as hooks, folds, ribbons or loops of material sewed to the fabric of the drapery, may be employed if desired. The end 11 of the overdrap portion 8 may be closed by stitching, as

may also the lower end 12. It may be desired, as shown in Figure 2, to have the overdrap portion 8 contrast with the main portion of the drapery, in which case the main portion may be knitted or otherwise fabricated in some figured pattern 13 while the overdrap portion 8 may be left plain.

Although so illustrated in Figures 1, 2 and 3, it is obviously not necessary to support decorative hangings comprising the invention from one of the ends of the tubular fabric which were open when the fabric was knitted or otherwise manufactured. It is no less feasible, as in the embodiment shown in Figure 4, to hang it from one of the other edges, for which purpose such edge may be provided with any suitable supporting means, such as the fold 14 and rod 15. The open ends of the fabric may in such case be left open or may be closed by suitable stitching 16, as may be preferred. An interlining comprising one or more sheets of other fabric, as illustrated by the lining 17, may if desired be employed. While such interlining is shown only in Figure 4, it is apparent that it may be incorporated in any curtains, draperies, hangings, or other articles embodying the invention, as, for example, in those of Figures 1, 2 and 3.

It is obvious that numerous changes may be made in the embodiments shown and, in fact, that various other embodiments of the invention may be devised without in any way departing from the spirit of the invention. For example, the doubled edges 18 of any curtain, drapery, hanging or similar article made according to the invention may be suitably stitched; for example, for the purpose of simulating a self-lined curtain, drapery, or hanging or other corresponding article manufactured from two independent pieces of fabric. Likewise, the doubled edges 18 may, if desired, be cut and later stitched together to give the same effect. As indicated in connection with the description of Figure 4, the ends of the tubular fabric which were open when the fabric was produced may be closed by suitable stitching or left open. It is entirely possible to knit or otherwise incorporate a finished edge in tubular fabric of this kind, in which case it may not be necessary or desirable to close the originally open ends. Fringe, braid, or other material may be applied to any end or edge for the purpose of enhancing the decorative effect. Various designs other than those illustrated and various dyeing or printing effects may be used. The seamless tubular fabric may conveniently be left in the condition in which it leaves the fabricating ma-

chine or it may be pressed or otherwise finished to cause it to assume and retain a flat shape.

Curtains, draperies, hangings, or like articles made in this manner may be of any material which can be knitted or otherwise fabricated into seamless tubular cloth. In the case of rayon, for example, very attractive curtains, draperies, hangings, or like articles of excellent draping qualities can be manufactured according to the invention at very low cost. Cotton, wool, silk and other natural or artificial materials may, however, be employed instead. If desired, combinations of two or more different materials may be employed in the manufacture of a single piece of tubular fabric, in which case novelty effects may be provided, either directly or by cross-dyeing. In general, any material or materials that can be fabricated into seamless tubular fabric may be employed in the practice of the invention.

It is obviously not necessary that the curtain, drapery, hanging or other article be supported in such manner that it falls straight, as illustrated in the drawing, for ruffles, folds, pleats, etc., may be introduced either before or during the hanging operation. If desired, tie-backs of the same or a contrasting material may be employed, in which case the highly desirable draping qualities inherent in curtains, draperies, hangings or the like manufactured pursuant to the teachings of the invention are brought out to even better advantage. It is also possible to apply the hanging to a roller such as commonly used in window shades in order to permit it to be rolled up if and when desired. Various other ways of hanging

or otherwise supporting curtains, draperies, or other articles manufactured in accordance with the invention will occur to those skilled in the art.

It is intended that the patent shall cover, by suitable expression in the appended claims, whatever features of patentable novelty reside in the invention. 5

What is claimed is:

1. A decorative hanging such as a curtain, drapery or the like comprising a seamless, circularly knit, continuously formed fabric flattened to form a collapsed tube and thereby present in close relation to each other opposite side portions which form the front and back sections of the hanging, said hanging having its opposite side portions joined along their longitudinal edges by fabric portions integral with the side portions, having both ends closed to assure flatness of the hanging, and having along one edge attaching means by which it may be suspended. 10 20

2. A decorative hanging such as a curtain, drapery or the like comprising a seamless, circularly knit, continuously formed fabric flattened to form a collapsed tube and thereby present in close relation to each other opposite side portions which form the front and back sections of the hanging, said hanging having its opposite side portions joined along their longitudinal edges by fabric portions integral with the side portions, having at least one end closed to assure 25 30 flatness of the hanging, and having along one edge attaching means by which it may be suspended.

GEORGE F. BROOKS.
